Des. 178,681
Patented Sept. 4, 1956

178,681

COSMETIC POWDER JAR

Douglas F. Linsley, Westport, Conn.

Application September 7, 1955, Serial No. 37,836

Term of patent 7 years

(Cl. D86—10)

Fig. 1.

Fig. 2.

Fig. 3.

Fig. 1 is a top plan view of a cosmetic powder jar showing my new design;

Fig. 2 is a rear elevation thereof, and

Fig. 3 is a side elevation of the jar.

I claim:

The ornamental design for a cosmetic powder jar, substantially as shown.
